[57] CLAIM

The ornamental design for a combination eraser and marker holder, as shown and described.

DESCRIPTION

FIG. 1 is a top plan view of a combination eraser and marker holder showing my new design;

FIG. 2 is a side elevational view thereof, the other side being a mirror image of the illustrated side;

FIG. 3 is a bottom plan view thereof; and,

FIG. 4 is an end view thereof, the other end being a mirror image of the illustrated end.

The writing implements depicted by means of broken lines in FIGS. 1 and 4 have been shown for illustrative purposes only and form no part of the claimed design.
